UNITED STATES PATENT OFFICE.

CHARLES DE LUKACSEVICS, OF NEW YORK, N. Y.

DESIGN FOR A SIPHON-HEAD.

No. 38,515.

Specification for Design.

Patented April 9, 1907.

Application filed March 5, 1907. Serial No. 360,793. Term of patent 14 years.

To all whom it may concern:

Be it known that I, CHARLES DE LUKACSEVICS, a citizen of the United States, residing at New York, in the county and State of New York, have invented a new, original, and ornamental Design for Siphon-Heads, of which the following is a specification, reference being had to the accompanying drawing, forming part thereof.

The figure is a side elevation of a siphon-head, showing my new design.

I claim—

The ornamental design for a siphon-head, as shown.

CHARLES DE LUKACSEVICS.
